UNITED STATES PATENT OFFICE.

CONRAD ZWICKEL AND LEO P. GRUNBAUM, OF BOISE, IDAHO; SAID ZWICKEL ASSIGNOR TO SAID GRUNBAUM.

NON-REMOVABLE BUNG.

SPECIFICATION forming part of Letters Patent No. 691,227, dated January 14, 1902.

Application filed July 30, 1901. Serial No. 70,258. (No model.)

To all whom it may concern:

Be it known that we, CONRAD ZWICKEL and LEO P. GRUNBAUM, citizens of the United States, and residents of Boise, in the county 5 of Ada and State of Idaho, have invented a new and Improved Non-Removable Bung, of which the following is a full, clear, and exact description.

The object of this invention is to provide 10 a bung for wooden receptacles for malt or other liquors or any liquid which is non-removable without its destruction after the bung has been driven into the bung-hole of a barrel, cask, or keg used for containing such 15 liquors or liquids, whereby the adulteration of a choice brand of malt or other liquor or liquid is prevented or exposed by the necessary substitution of a differently-constructed bung entailed by the mutilation of the improved bung upon its removal from the packing vessel.

The invention consists in the novel construction and combination of parts, as is herein-after described, and defined in the appended 25 claims.

Reference is to be had to the accompanying drawings, forming a part of this specification, in which similar characters of reference indicate corresponding parts in both figures.

30 Figure 1 is a reverse plan view of a bung held in place in a bung-hole by the improvement, and Fig. 2 is a transverse sectional view substantially on the line 2 2 in Fig. 1.

The device may be applied to bungs formed 35 of any suitable material—such, for example, as hard wood.

In the drawings, A indicates a portion of a barrel-stave at the chime of the barrel, having the bung-hole A' therein.

40 The bung 10 is fitted to the bung-hole A' so as to permit the bung to receive a patching or jacket of coarse fibrous material 11, which will cover the side and inner end of the bung and may be coated, as is usual, with a suitable cement, which will render the bung-hole 45 or aperture liquid-tight when the bung and patching on it are together forcibly inserted into the bung-hole A'.

The invention consists of a locking device 50 formed of a strand of resilient wire or other suitable material that is not liable to rust

and of proper gage to render the completed locking device effective in service.

As shown, at a point suitably distant from one end a of the wire strand the material is 55 bent to form a loop or bow b and two substantially parallel straight members c c', the end a having an inward curve thereon. From the point c², that is the termination of the straight limb c', the wire material is bent outward to form an obtuse angle at said point, and thence it is gradually curved, as at c³, to extend the same to a point c⁴, from which the wire rod is curved, so as to form a nearly true circle c⁵, that nearly equals in diameter the 60 diameter of the inner end of the bung 10.

At d the curvature of the wire strand is changed in radius, so as to define an arc d' of a smaller circle, and at d² the strand crosses the similarly-curved portion c³, already described, the portion d' merging into the obtuse angle d³, from which the material is outwardly extended, as a straight limb d⁵, which merges into the bowed formation e, that is positioned directly opposite the bowed portion b. 70 75

A nearly straight member e' is extended inwardly from the bowed portion e and it passes beneath the curved end a of the wire material.

The peculiarly-bent locking-piece that has been described is secured upon the inner end 80 of the bung 10 before it is driven into the bung-hole of a barrel or the like by means of two wire staples 12.

As shown, the staples 12 are each formed of such width between the legs 12^a thereof as to 85 permit the staple to pass over the straight limbs of the respective loops b e and thence into the body of the bung 10, the ends of each staple being clenched and embedded in the bung near its outer side, as shown at 12^b in Fig. 2. 90

The peculiar construction of the locking device for the bung renders the bowed portions b e spring-pressed locking-dogs, which normally project exterior of the periphery of the bung 10, whereon they are loosely held. 95 When the bung is to be inserted within the bung-hole A', the bowed portions or dogs b e are pressed inwardly, so as to bear upon the wall of the bung-hole. The bung, with the patching on it, is now forcibly driven into the 100 bung-hole, and when the dogs b e pass below the inner edge of the bung-hole said dogs by

spring-pressure upon them are forced outward into normal adjustment, which will hook them over the stave material at and near the bung-hole A'. It will be seen that to remove 5 the bung 10 the bung must be mutilated or completely destroyed, and as there may be a trade-mark or other safeguard against substitution placed upon the exterior of the bung it is obvious that the exchange of another 10 bung for the one destroyed will be readily detected, so that the use of the improved bung will effectually prevent adulteration of the original package or the substitution of inferior liquor for that of a choice brand pro- 15 tected by the improvement.

Having thus described our invention, we claim as new and desire to secure by Letters Patent—

1. A non-removable bung, comprising a cylindric body, a resilient coiled-wire locking device having looped ends that project oppo-

sitely beyond the lower end of the body, and means to secure the locking device on said end of the body so that the looped ends may be retracted against the spring of the coiled 25 wire they are formed upon.

2. A non-removable bung, comprising a cylindric body, a locking device bent from a wire strand so as to provide two opposite looped members or dogs thereon, which are 30 normally spring-pressed beyond the periphery of the bung, and staples adapted to hold the locking device secured upon the inner end of the bung-body.

In testimony whereof we have signed our 35 names to this specification in the presence of two subscribing witnesses.

CONRAD ZWICKEL.
LEO P. GRUNBAUM.
